UNITED STATES PATENT OFFICE.

HUGO A. BUCCINI, OF PHILADELPHIA, PENNSYLVANIA, ASSIGNOR TO VICTORY LAMP COMPANY, OF PHILADELPHIA, PENNSYLVANIA.

DESIGN FOR A COMBINED LIGHTING FIXTURE AND MAIL BOX.

Application filed August 31, 1927. Serial No. 23,254. Term of patent 3½ years.

To all whom it may concern:

Be it known that I, Hugo A. Buccini, a citizen of the United States, and a resident of Philadelphia, county of Philadelphia, State of Pennsylvania, have invented a new, original, and ornamental Design for Combined Lighting Fixture and Mail Box, of which the following is a specification, reference being had to the accompanying drawing, forming a part thereof.

Figure 1 is a perspective view of a com-

bined lighting fixture and mail-box embodying the design of the present invention; and

Figure 2 represents a side elevation of the same.

I claim:

The ornamental design for a combined lighting fixture and mail-box substantially as shown.

HUGO A. BUCCINI.
